HAROLD CRUGER, OF RIDGEWOOD, NEW JERSEY

DESIGN FOR A TEXTILE FABRIC OR THE LIKE

Application filed November 8, 1932. Serial No. 45,817. Term of patent 8½ years.

To all whom it may concern:

Be it known that I, HAROLD CRUGER, a citizen of the United States, residing at 263 Franklin Avenue, Ridgewood, Bergen County, State of New Jersey, have invented a new, original, and ornamental Design for a Textile Fabric or the like, of which the following is a specification, reference being had to the accompanying drawing, forming part thereof.

The figure is a surface view of a piece of textile fabric or the like, showing the design.

The area within the dot and dash lines shows one complete unit of the design. The repeats are arranged in vertical rows, and adjacent vertical rows are one half a complete unit offset so that the angle of the complete unit indicated by letter A corresponds with angle B of one of the repeats in an adjacent vertical row.

I claim:

The ornamental design for a textile fabric or the like, as shown and described.

HAROLD CRUGER.
